SPINNING UNIT

Frederick Kent, Glen Rock, N. J., assignor to
Sipp-Eastwood Corporation, Paterson, N. J., a
corporation of New Jersey

Application October 19, 1937, Serial No. 169,830

18 Claims. (Cl. 117—9.5)

This invention relates to that type of twisting unit by which a double twist is formed in the yarn, the yarn-mass holder being held in some way against rotation and there being a rotor coaxial therewith and the yarn being extended and travelling from the holder axially through the wound mass in one direction, then laterally through a flier portion of the rotor, and then in a direction opposite to the first direction exterior of the mass and to a guide, one twist forming between the yarn mass and the flier and the other between the flier and the guide. For instance, see my application Serial No. 102,792.

Heretofore the portion of the yarn which extends from the flier to the guide has been free to balloon without restraint and there has been no provision for protecting such portion not only against atmospheric air currents but against the actual resistance of even static air. Further, difficulty has been met with in the effort to provide a proper tensioning of the yarn within the unit. In view of these considerations it has been regarded as impossible to double-twist, after the manner indicated, certain yarns without disruption thereof or abrading them or subjecting them to such change in character as to affect their appearance and their quality properly to absorb dyes. Such yarns, for instance, are acetate yarns in which the component filaments are almost parallel or without substantial binding twist and more easily distorted or injured than those of yarns whose filaments are of the natural class.

According to this invention I have provided a spinning unit in which the portion of the yarn which would otherwise form a balloon of more or less extent, according to the rotary speed of the flier, is definitely confined and further protected from both currents and the resistance of atmospheric air and in which the portion of the yarn actually contained in the unit is properly tensioned, such tensioning being further accomplished in a manner extremely simple and requiring no independently movable parts. Preferably the rotor flier is the actual confining means and it has a flexible and elastic connection with the axial portion or spindle of the rotor which enables the flier to find its own center of balance when the rotor attains a given speed.

The flier portion of the rotor is further so devised that there is a novel controlled flow or progress of the yarn in the lateral direction.

In the drawings,

Fig. 1 is a side elevation of the improved spinning unit displaced from its normal or tilted to the vertical position;

Fig. 2 is a view showing the unit mainly in vertical diametric section;

Fig. 3 is a side elevation of the rotor with shell 22 removed and Fig. 4 a plan thereof partly broken away and with conduit 28 removed;

Fig. 5 is a plan of one of the half-disks 26;

Fig. 6 is an elevation of strip 28;

Fig. 7 is a fragmentary side elevation of the lower portion of the rotor flier;

Fig. 8 is a fragmentary vertical sectional view of parts 22, 23, and 24;

Fig. 9 is a side elevation of the upper portion of the yarn-holder core 32; and,

Fig. 10 is a vertical sectional view of the bearing 34 and parts adjacent the same.

The three main parts of the unit are the stator, or fixed structure; the rotor journaled in the stator and including a flier which conducts the yarn, after passing in one direction axially through the yarn mass, generally laterally and then in the opposite direction for travel thereupon through a guide independent of the unit; and a yarn-mass holder which is coaxial with but is withheld from rotation with the rotor.

The stator.—The rail 1 carried by brackets 2a on vertical uprights 2 in inclined position (the uprights being assumed to be vertical parts of the machine including the spinning unit) receives the depending hollow shank 3 of the bolster whose upper portion includes a housing 4 having an upstanding flange 5. The shank is closed at its lower end by a plug 6 and thus forms an oil well which may be filled at nozzle 7. The bolster has an upper ball-bearing 8 and, in the plug, a lower bearing 9. The shank is held to the rail normally in perpendicular relation thereto but is susceptible of some angular displacement as an incident of vibration, thus: Between the rail and housing are gaskets 10 of which the intermediate one is elastic, as rubber; below the rail is a nut 11 screwed on the shank and between the rail and nut is a helical spring 12 interposed between two washers 13. Fixed in the housing is the field 14 of an electric motor whose wiring may enter a hole 15. A part of the stator is preferably a cylindrical shield 16 of indurated paper or the like stiff light material whose lower end is telescoped into the flange 5 and rests on lugs 5a of the flange, having a top stiffening bead 6a.

The oil-well in the shank is tapered downwardly so that when the spindle is in rotation the oil, under centrifugal force created by the spindle, will be elevated to the upper bearing 8.

The rotor.—This comprises a spindle and a flier.

The spindle, 17, is journaled in the bearings 8

and 2 and projects upwardly from the housing and lies actually above the flange 4 and has the armature 18 arranged to coat with the field 14. Since the rail 1 is inclined the spindle is tilted.

The fier comprises a diaphragm fixed to the spindle just above the armature and a cylindrical shell supported by the diaphragm and concentric with and extending above the spindle. The diaphragm comprises a disk 18 having an upward standing peripheral flange 18a and its under side formed adjacent its periphery with a wide rabbet, and an annular disk or flat annulus 20 occupying and fixed in the rabbet and having a depending flange 20a, there being a crevice 21 between the parts 18 and 20. The shell, 22, is snugly telescoped at its lower end into the flanged disk 18 and here rigidly secured therein and it is provided at its inner side with a vertical strip 23 having at its upper end a yarn guide 24 (Fig. 8) arranged in a stiffening bead or rim 21a at the top of the shell. The diaphragm is formed of some light, indurated, flexible and elastic material so that the fier may undergo some angular displacement and so, when the rotor attains a given speed, find its center of balance. Crevice 21 permits flexion of disk 18 without obstruction by the annulus. The shell may be composed of indurated paper or the like stiff, light material. The strip 23 provides a bore 23a which constitutes the terminal portion of a duct 25 which is otherwise formed to extend from the upper end of and down through the spindle axially thereof (Fig. 2) to near the level of the diaphragm, where it is then gradually diverted, as in a curve, and extends in a horizontal spiral (see Fig. 4) through the diaphragm. To form this duct in the diaphragm the under sides of the disk 18 and annulus 20 are channeled (see Fig. 4, showing the disk broken away and the annulus in section in a plane through that portion of duct 25 which forms the channel in the annulus) and such channel is closed by a pair of half-disks 26 which are secured against the under sides of the disk and annulus by a spring-ring 27 engaged in a groove at the inside of the flange 20a of the annulus. Said duct is preferably lined by a conduit 28 in the form of a cross-sectionally round wire developed as a long helical coil with its convolutions here close together so that the surface of the passage formed by the conduit is corrugated. This passage not only permits the travel therethrough, without obstruction incident to joints between the parts of the rotor, of a flexible wire-like yarn-threader, but it has a quite important function hereinafter to be explained.

The yarn-mass holder.—This comprises, generally stated, a discal base portion to support the wound mass (as windings of yarn on a spool) and an axial portion to be received in the bore of said mass. Bearings are to exist between the spindle portion of the rotor and such holder, spaced from each other axially of the rotor and mass, as one above the other, and both of these should be accommodated in the holder in such manner as not to require the bore of the mass to be of excessive diameter. Further, said axial portion of the holder should protrude from the wound mass so that its protruding (and hence non-rotating) terminal will afford stationary contact for the yarn where it begins its travel in the direction through the bore of the mass. The holder is constructed with these observations in view and may be regarded as formed in two main sections, a lower section comprising, with a disk

(affording the said base) in which one bearing is contained, a central stem, and an upper section including a tubular end or terminal to telescope over said stem and in which the other bearing is contained, the other terminal of such section being adapted to protrude from the bore of the mass to afford the said stationary contact for the yarn. The holder is to be held against rotation.

28 is the disk of the lower section and 30 its said stem, formed tubular to receive the spindle 17. The disk has a segment 28a thereof weighted and it accommodates one of said bearings, as a ball-bearing 31; 31a is an elastic, as rubber, bushing between the disk and the outer race of the bearing. The upper section comprises a cylindrical metal core 32 having an axial bore 32a and enclosed in a sleeve 33 normally rigidly secured thereto and depending below the core and thus forming the said tubular terminal of said section, the same being telescoped over the stem 28 and abutting the disk 28. Within said terminal is accommodated the other bearing 34, as a ball-bearing, such coating with the first bearing to maintain the holder constantly in axial relation to the spindle; the inner race of this bearing is confined between a shoulder of and a nut 35 screwed on the spindle. There is an elastic bushing 36 between the bearing and sleeve. (Access to the nut may be had by slipping the upper section off the stem of the lower section, which however it snugly fits). The part 37, forming no part of the invention, is a stub-detector pivoted to the core 32 which protrudes from the wound mass and affords the said stationary contact for the yarn, such part being adapted to enter a notch 37a in the core when in detecting position.

In the preferred form there is a cylindrical shell 38 carried by the base (disk 28) of the yarn-mass holder, being telescoped thereover, as shown, and fastened thereto, and this may have a removable cap 38a. The shell may be of indurated paper and the cap of some transparent material.

The cap being removed and the yarn mass a (as a core x around which the yarn is wound) fitted over the axial portion of the yarn-mass holder and left resting on its base (disk 28), with the aid of a yarn-threading device or "snake" the 45 yarn is directed down through the bore 32a of the upper section of the holder and through passage 25 of the rotor and is then extended through the usual guide 39 arranged above the spinning unit. When the unit is operating, a twist forms 50 in the portion of the yarn between the wound mass and the fier as the latter rotates relatively to the former and another twist forms in the portion of the yarn between the fier and the guide 39.

Instead of the yarn, having travelled axially through the yarn mass in one direction, being free to balloon as to the portion thereof which is travelling toward the guide 39 in the opposite direction and exterior of the mass, it is by this invention 55 confined within a definite orbit, to wit, defined by the part 22 here actually formed to surround the mass and which further shields said portion not only with respect to air exterior of such part but (because of strip 23) with respect to air 70 within the same.

Again, instead of the yarn, having travelled through the yarn mass axially thereof, being free to move thereupon laterally subject to no resistance to the tendency of centrifugal force 75

to cause it to drive it laterally (with the likelihood of its piling up in and clogging the passage of the conduit 28 in the case where, as here, the passage is next diverted to proceed along the inside of the shell), it is caused to be gradually diverted away from the radial direction by a wall of the rotor which faces the rotor axis and is itself diverted thus gradually from the latter, or here actually spirally formed, such wall being taken as that side of said passage which corresponds to the outer side 25a of the portion of duct 25 which is formed in the diaphragm of the rotor. In short, for the yarn to travel laterally from the rotor axis it must undergo friction as to an appreciable extent of its length and by contact with such wall. Practice has shown that this feature of my invention is indispensable at the high speed at which the rotor is driven (7200 R. P. M.), especially when acetate and the like yarns are being treated.

Further, a factor in producing tension on the yarn, which tension is largely an incident of centrifugal force acting to hold it outward against the surface of the conduit 28 within bore 23a, is the diversion it undergoes due to the mentioned wall and the friction between it and such wall.

If it be attempted to have the yarn flow or progress through a passage providing a smooth surface and which undergoes more or less diversion, especially such as characterizes the present passage 25 where it enters, passes spirally through and leaves the diaphragm, I find in practice that such is impossible, especially in the case of acetate yarns, due to the adhesion set up. But when the passage surface (especially at each bend) is formed transversely corrugated, as when the conduit 28 is present and it is formed of cross-sectionally round wire, this difficulty is completely overcome and the progress of the yarn is smooth-running.

In view of the high speed at which the rotor is driven and the form of its flier portion, here not only developed to flank the wound mass but actually formed as a shell supported at one end and representing appreciable mass, it is found very necessary to connect such flier portion with the axial portion or spindle of the rotor by flexible elastic means, as the described diaphragm, so that when a given speed is attained it may find its center of balance. Without such connection the flier would not only have to be balanced with extreme accuracy but so constructed that such balance could not be disturbed by handling or other cause, since otherwise undue vibration would attend its rotation.

The shell 38 and cap 38a are present to protect the portion of the yarn which is at any time immediately paying off from the wound mass from disturbing currents of air created by the rotating shell 22.

Shield 16 both protects shell 22 against accidental disturbance by the operator and insulates it from exterior moving or static air.

Having thus fully described my invention what I claim is:

1. A yarn twisting unit including supporting structure, a rotor journaled in and having a spindle projecting from said structure, and a holder spaced from said structure and receiving the spindle and confined by the rotor to coaxial relation with the spindle and carried by and normally held from the rotation with the rotor and supporting the wound mass of yarn to be twisted in substantially coaxial relation to the spindle, said spindle having a yarn passage ex-

tending therethrough first toward said structure and then diverted into coincidence with the space between the latter and said holder, and said unit having means, arranged to flank the mass, for confining within a given orbit the portion of the yarn which, upon issuing from the diverted part of said passage, is directed from said structure.

2. A yarn twisting unit including supporting structure, a rotor journaled in and having a spindle projecting from said structure, and a holder spaced from said structure and receiving the spindle and confined by the rotor to coaxial relation with the spindle and carried by and normally held from rotation with the rotor and supporting the wound mass of yarn to be twisted in substantially coaxial relation to the spindle, said spindle having a yarn passage extending therethrough first toward said structure and then diverted into coincidence with the space between the latter and said holder, and said rotor having means, arranged to flank the mass, for confining within a given orbit the portion of the yarn which, upon issuing from the diverted part of said passage, is directed from said structure.

3. A yarn twisting unit including supporting structure, a rotor journaled in and having a spindle projecting from said structure, and a holder spaced from said structure and receiving the spindle and confined by the rotor to coaxial relation with the spindle and carried by and normally held from the rotation with the rotor and supporting the wound mass of yarn to be twisted in substantially coaxial relation to the spindle, said spindle having a yarn passage extending therethrough first toward said structure and then diverted into coincidence with the space between the latter and said holder, and said rotor having a shell arranged to surround the mass and confine within a given orbit the portion of the yarn which, upon issuing from the diverted part of the passage, is directed from said structure.

4. The unit set forth in claim 3 characterized by said shell presenting in any section thereof transverse of the rotor a substantially circular form and being substantially concentric with the rotor.

5. A yarn twisting unit including supporting structure, a rotor journaled in and having a spindle projecting from said structure, and a holder spaced from said structure and receiving the spindle and confined by the rotor to coaxial relation with the spindle and carried by and normally held from rotation with the rotor and supporting the wound mass of yarn to be twisted in substantially coaxial relation to the spindle, said rotor having a portion thereof arranged to flank the mass and a yarn passage extending through the spindle substantially axially thereof and toward said structure, then diverted into coincidence with the space between the latter and the holder, and then directed in substantially the direction in which the spindle projects from said structure, said rotor portion confining the part of the yarn lateral of the spindle and travelling in said direction against centrifugal displacement.

6. The unit set forth in claim 5 characterized by said portion being a shell surrounding the mass.

7. The unit set forth in claim 5 characterized by said portion being a shell presenting in any section thereof transverse of the rotor axis a substantially circular form and being substantially coaxial with the rotor.

8. A yarn twisting unit including supporting structure, a rotor journaled in and projecting

- from said structure, and a holder spaced from said structure and carried by and normally held from rotation with, and supporting the wound mass of yarn to be twisted in substantially coaxial relation to, the rotor, said rotor having a 5 yarn passage extending therethrough first toward said structure and then diverted into coincidence with the space between the latter and said holder, and said rotor including an axial portion, a shell, 10 arranged to surround the mass and confine within a given orbit the portion of the yarn which, upon issuing from the diverted part of said passage, is directed from said structure, and elastic flexible means supporting the shell on said axial portion.
15. A yarn twisting means including in combination, with supporting structure, a rotor having an axial portion journaled in said structure, and means, with reference to which the rotor rotates, for supporting the wound mass of yarn to be 20 twisted in substantially coaxial relation to the rotor, said rotor including a yarn filer portion which projects lengthwise of said axial portion and is arranged to flank the yarn mass and said portions having a flexible elastic connection with 25 each other.
10. A yarn twisting means including in combination, with supporting structure, a rotor having an axial portion journaled in said structure, and means, with reference to which the rotor rotates, 30 for supporting the wound mass of yarn to be twisted in substantially coaxial relation to the rotor, said rotor including a shell-like yarn filer portion arranged to surround said mass and said portions having a flexible elastic connection with 35 each other.
11. A yarn twisting means including in combination, with supporting structure, a rotor having an axial portion journaled in said structure, and means, with reference to which the rotor rotates, 40 for supporting the wound mass of yarn to be twisted in substantially coaxial relation to the rotor, said rotor including a shell-like yarn filer portion arranged to surround said mass and a flexible elastic diaphragm connecting said portions. 45
12. A yarn twisting means including in combination, with supporting structure, a rotor journaled therein and having a bore extending lengthwise of its axis, and a holder, with reference to 50 which the rotor rotates, for supporting the wound mass of yarn to be twisted in substantially coaxial relation to the rotor, said holder including a shell formed and arranged to surround the yarn mass and said rotor having a passage extending laterally from said bore for discharge 55 therefrom of yarn travelling from the mass through the bore.
13. A yarn twisting means including in combination, with supporting structure, a rotor journaled therein and having a bore extending lengthwise of its axis, and a holder, with reference to 60
- which the rotor rotates, for supporting the wound mass of yarn to be twisted in substantially coaxial relation to the rotor and formed to substantially completely enclose the mass and said rotor having a passage extending laterally from said bore for discharge therefrom of yarn travelling from the mass through the bore. 5
14. A rotor for a yarn twisting unit having a 10 yarn passage extending through the rotor first generally lengthwise of and then in a line gradually diverted from and extending around the rotor axis, that part of the passage which extends around said axis defining a yarn guiding wall also extending around and facing toward said axis.
15. A yarn twisting unit including supporting 15 structure, a rotor journaled therein and projecting from said structure and having an axial bore, a holder spaced from said structure and carried by and normally held from rotation with, and supporting the wound mass of yarn to be twisted 20 in substantially coaxial relation to, the rotor, said rotor having a portion thereof arranged to flank the mass and a passage extending laterally from said bore in coincidence with the space between said structure and holder for discharge from the 25 bore of yarn travelling from the mass through the bore, and said holder having a shell arranged to surround the mass and interposed between the same and said portion.
16. A yarn twisting unit including supporting 30 structure, a rotor journaled in and projecting from said structure, a holder spaced from said structure and carried by and normally held from rotation with, and supporting the wound mass 35 of yarn to be twisted in substantially coaxial relation to, the rotor, said rotor having a yarn passage extending therethrough first toward said structure and then diverted into coincidence with the space between the latter and said holder, and said rotor having means, arranged to flank the 40 mass, for confining within a given orbit the portion of the yarn which, upon issuing from the diverted part of said passage, is directed from said structure, and a shell carried by said structure and arranged to surround the yarn mass 45 and the rotor.
17. A rotor for a yarn twisting unit including a spindle and a portion extending laterally beyond the spindle perimeter, said spindle having a bore extending lengthwise therethrough which terminates in a diverted discharge end and said portion having a wall providing a yarn-contact surface facing inwardly toward but gradually diverted from the axis of the spindle and arranged to afford contact for yarn issuing from the diverted portion of the passage. 50
18. The rotor set forth in claim 17 characterized by said yarn-contact surface also extending around said axis. 55

FREDERICK KENT.
